Primary Examiner — Catherine Tuttle(74) *Attorney, Agent, or Firm* — Booth Udall Fuller, PLC(57) **CLAIM**

The ornamental design for a rotating ride-on toy, as shown and described.

DESCRIPTION

FIG. 1 is a perspective view showing my new design for a rotating ride on toy with the puck element in position on the main body portion of the toy;

FIG. 2 is a perspective view similar to FIG. 1 but showing the puck separated from the main body of the toy;

FIG. 3 is a perspective view showing the puck in an alternate separated position relative to the main body of the toy;

FIG. 4 is a rear elevation view of FIG. 3, showing the cutout portion of the puck edge;

FIG. 5 is a front elevation view thereof;

FIG. 6 is a side elevation view thereof;

FIG. 7 is a top plan view thereof;

FIG. 8 is a bottom plan view of FIG. 1;

FIG. 9 is a bottom plan view of FIGS. 3-6;

FIG. 10 is a cross sectional view of the puck element, taken along line 10-10 of FIG. 11;

FIG. 11 is an enlarged scale, upper perspective view of the lower portion of FIGS. 3-6;

FIG. 12 is an enlarged scale elevation view of the portion of FIG. 4 as indicated by dashed line circle 12;

FIG. 13 is an enlarged scale elevation view of the handle portion of FIG. 6, indicated by the dashed line circle 13; and, FIG. 14 is an enlarged scale elevation view of the puck portion of FIG. 6 indicated by dashed line circle 14.
